CLEVELAND W. WOODLAND, OF LIND, WASHINGTON.

WELL-DRILLING TRIP.

1,253,327.

Specification of Letters Patent. Patented Jan. 15, 1918.

Application filed May 16, 1917. Serial No. 169,071.

To all whom it may concern:

Be it known that I, CLEVELAND WALTER WOODLAND, a citizen of the United States, residing at Lind, in the county of Adams 5 and State of Washington, have invented certain new and useful Improvements in Well-Drilling Trips, of which the following is a specification.

This invention relates to an improvement 10 in well drilling trips, and more particularly to a device of this character intended for use to act directly upon the cable or line by which the string of tools is suspended, to alternately take the cable in and then slacken 15 the same, the mechanism being so formed that the device may be fitted to derive power from a constantly revolving shaft.

An object of my invention is to provide a mechanism of the character set forth which 20 has parts thereof so arranged that the cable carrying the string of tools will be drawn in and then automatically released to leave the tools substantially free and unhampered by excessive weight, which will allow the drill 25 to strike a harder blow at the bottom of the hole without the necessity of excessive weighting of the tool as required in the use of cam and treadle or walking beam types of drilling machines.

30 A further object resides in constructing the parts in such a way that a small part of the weight of the drilling tool will return the released parts to the starting position where the cable is slackened and from which 35 position the parts will be again moved to draw in the cable.

Yet another object is to provide means by 40 which even the most minute adjustment of the length of stroke of the drilling tool can be obtained, and in constructing the parts in such a manner that the cable by which the string of tools is carried can be lengthened or let out as the drill deepens the bore.

45 A still further object is to provide means by which the parts are rendered inoperative to raise and lower the drill even during the rotation of the shaft from which power is derived.

With the above and other objects in view, 50 which will be in part described and in part understood from the specification, drawings, and claims, my invention consists in certain novel features of construction and combinations of parts which will be hereinafter more 55 fully set forth.

In the drawings:

Figure 1 is a view in elevation showing the invention set up for use;

Fig. 2 is a top plan view of parts shown in Fig. 1;

Fig. 3 is a detailed view showing the ratchet hub;

Fig. 4 is a view in end elevation of the hub;

Fig. 5 is a view in perspective showing the trip lever with the trip pawl fitted in place thereon; and,

Fig. 6 is a view in perspective showing the trip lever lock.

The power shaft 1 is mounted on the bearing standards 2 and 3, and this shaft may be connected to have the revoluble movement directly transmitted thereto or might have a geared or belted connection. A trip cylinder 4 is loosely mounted on the shaft 1, and a ratchet hub 5 is secured on the shaft by means of a key 6, or in any other way, to turn with the shaft and with the ratchet portion thereof within the trip cylinder 4.

Bearing standards 7 and 8 are carried on the outer wall of the trip cylinder 4 and are disposed to extend substantially radially, the trip lever 9 being mounted between these standards and pivoted in place by the bolt or pin 10. A trip pawl 11 is mounted on one end of the trip lever 9 and has a sliding fit through an opening 12 provided through the wall of the trip cylinder, a compression spring 13 being mounted between the cylinder and the outer edge of the lever 9 to normally urge the lever to swing to a position that the end of the trip pawl 11 is engaged with the teeth of the ratchet hub 5. The power shaft 1 has revoluble movement in a counter-clockwise direction as the parts are shown in Fig. 1, and thus as the trip pawl 11 engages with the teeth of the ratchet hub 5, the trip cylinder 4 will be locked to turn with the power shaft 1.

The trip cylinder has a cable lever 14 extending radially therefrom, and a cable guard 15, and a pulley 16 are carried by and mounted in place thereon to receive the cable 17. The line or cable 17 is run over or around the pulley 16 and at the remaining end has the string of tools suspended. It will of course be understood that the cable will be rove through or passed over a pulley on a derrick or other suitable structure, and as the power shaft 1, turns, the lever 14 will

be swung to raise the tools through tightening or drawing in the cable, however some means must be provided to release the cylinder 4 from its setting to turn with the shaft, 5 due to the fact that the shaft 1 is constantly rotating. With this purpose in view, I provide a lever 18, which is held by a pin 19 or other suitable means to be capable of swinging movement, and which has a lock 20 thereon to engage with the teeth of the 10 segmental rack 21 so that as the adjusting lever 18 is swung to various positions it will be retained in the set position until again manually adjusted. A chain 22 is connected, 15 by means of a clevis 23, or in some other suitable way, with the lever 18 at a point spaced from the mounting on the bolt 19, and at its remaining end the chain 22 has connection with the outer end of the trip 20 lever 9, through medium of a clevis 24, or in some other suitable way. The adjusting lever 18 is stationed at one side and somewhat spaced from the mounting of the shaft 1, substantially after the arrangement illustrated in Fig. 1, and as the trip cylinder 4 is turned through being locked with the ratchet hub 5, the cylinder will carry with the shaft until the slack of the chain 22 has been taken up, when this chain will exert a 25 sharp jerk against the outer end of the trip lever 9 and will force the same down against the pressure of the spring 13 to such a degree that the trip pawl 11 is raised from engagement with the teeth of the hub 5, when 30 the cylinder is released from its connection with the shaft 1. Upon release of the pawl 11 from the ratchet hub, the trip cylinder turns freely upon the shaft 1, and consequently the weight of the string of tools 35 40 upon the cable 17 will cause the lever 14 to be swung back sharply and the drilling tool will fall within the bore to bring the drill into operation, the fact that only a small part of the weight of the drilling tool is required to pull the lever back causing the 45 drill to strike a cutting blow with substantially its entire weight.

By swinging the adjusting lever 18 to one side or the other from the position 50 shown in Fig. 1, the degree of turning movement permitted in the trip cylinder to cause chain 22 to shorten to draw against the trip lever 9 will be varied and thus the length of the stroke of the drilling tool can be adjusted very quickly and without the necessity of disassembling any of the parts or stopping the operation of the mechanism. 55 To give greater latitude for adjustment of the length of stroke of the drilling tool, the 60 cable lever 14 has a plurality of openings 25 formed throughout the length thereof, and a bolt 26 is provided to be fitted through these openings to give desired adjustment to the relative spacing of the pulley 16 from 65 the center of turning of the cylinder 4. In

the present illustration, the pulley 16 is adjusted for a short stroke of the drilling tool, but as the pulley is adjusted to be mounted farther from the turning center of the cylinder, or nearer to the end of the cable lever 70 14, the cable will be taken in to a greater length and consequently a longer stroke will be given to the drilling tool. To insure that the trip pawl 11 will not be entirely withdrawn from the opening 12 in the trip cylinder, lugs or extensions 27 and 28 are provided on the trip lever and on the trip cylinder to come together and stop movement of the trip lever in its swinging path while the trip pawl is yet within the opening 12. 75 The compression spring 13 is fitted around these lugs and thus they are made to serve the dual purpose of holding the spring in the proper fitted position and insuring against excessive movement of the trip lever. 80

With the parts arranged in the manner above set forth, it will be seen that during the revolution of the shaft 1, the operation of the parts to cause reciprocatory movement of the drilling tool to be carried on 90 automatically, however, it may be desired under some circumstances to render the mechanism inoperative without stopping revolution of the power shaft 1, and with this purpose in mind I provide a trip lever 95 lock which is better illustrated in Fig. 6. This lock includes a substantially bell crank-shaped lever 29 which has a wedge-shaped cam portion 30 on one of the arms thereof, the member being pivoted by means of the 100 pin 31, on the trip cylinder 4 adjacent the opening 12. The member 29 is mounted in such a position that the wedge-shaped end 30 thereof can be swung and moved beneath the inner end of the trip lever 9, a spring 105 32 however being connected with the remaining arm of the member 29 to normally swing the lock to substantially the position shown in Fig. 2 where the wedge-shaped end, and in fact the entire structure, is 110 moved to one side of the trip lever 9. A cable of wire 33 is connected with the member 29 at the wedge-shaped end thereof and is then brought around the standard 8 and led out at one side so that it is presented 115 at all times in position to be readily accessible to the operator. When it is desired to stop the automatic operation, the cable or wire 33 is pulled to move the wedge-shaped end 30 of the member 29 beneath the inner end of the trip lever 9, the member 29 being swung against the tension of the spring 32. The wedge-shaped end 30, as it is disposed under the trip lever 9, will raise the same sufficiently against the pressure of the 120 spring 13, that the trip pawl 11 is withdrawn from the trip cylinder to such a degree that the inner end clears the teeth of the ratchet hub 5, and the shaft 1 and the ratchet hub can then turn freely within the cylinder 125 130

4. When the drawing force exerted upon the cable or wire 33 to move the member 29 and bring the wedge-shaped end thereof under the inner end of the trip lever is removed, the spring 32 will act to again swing the lock to the position shown in Fig. 2 and when the automatic operation of the parts will be resumed.

While in the present disclosure I have illustrated the cable 17 as being fitted through the cable guard and then around the pulley, it will be understood that connection might be made directly to the pulley, although it is desirable that the free end of the cable be extended off from the pulley to be payed out as the bore made by the drill is sunk deeper, and thus to insure that the drilling tool will at all times have a maximum efficiency. As it may be desired to change the length of stroke during operation of the mechanism, to accommodate the drilling tool for most efficient operation upon different strata as encountered in the bore, this can be accomplished by shifting the adjusting lever 18 to the left, as shown in Fig. 1, to lengthen the stroke and to the right to shorten the stroke.

From the foregoing it will be seen that I have provided a well drilling trip which can be applied and used in conjunction with derricks and tools now in use, and which has the operating parts formed in such a way that great latitude of adjustment to adapt the machine for the particular circumstances of use is had, and that the mechanism can be rendered inoperative at the will of the operator, while it will, when in use, accomplish substantially an automatic operation.

While in the foregoing I have shown and described only specific forms and construction of the parts, it will be understood that a number of changes and variations might be made in the form of the arrangement of the several members and in the manner of fitting and connecting the same for use, and hence I do not wish to be limited to the exact structure as herein set forth, but only such points as may be set forth and pointed out in the claims.

50 I claim:

1. A well drilling trip including in combination with a power shaft, a trip cylinder having a cable lever carried as a part thereof loosely mounted on said power shaft, a trip pawl by which the cylinder is locked to turn with the power shaft, means carried by the shaft with which the trip pawl locks, adjustable means carried by the cable lever by which a cable is held in conjunction therewith, and means to release the trip pawl to free the trip cylinder from the locked connection with the power shaft.

2. A well drilling trip including in combination with a power shaft, a trip cylinder loosely mounted on the shaft and provided

with a radially extending cable lever, a ratchet hub mounted in the trip cylinder and fixed to turn with the power shaft, means adjustably carried by the cable lever to have a cable held therearound, a trip pawl carried by the trip cylinder to engage with the teeth of the ratchet hub to lock the trip cylinder to be turned with the shaft, and means to release the trip pawl.

3. A well drilling trip including in combination with a power shaft, a trip cylinder loosely mounted on the shaft and provided with a radially extending cable lever, a ratchet hub mounted in the trip cylinder and fixed to turn with the power shaft, means adjustably carried by the cable lever to have a cable held therearound, a trip pawl carried by the trip cylinder to engage with the teeth of the ratchet hub to lock the trip cylinder to be turned with the shaft, means to release the trip pawl, and means to render the trip pawl inoperative.

4. A well drilling trip including in combination with a power shaft, a trip cylinder loosely mounted on the shaft, and provided with a radially extending cable lever, a ratchet hub mounted in the trip cylinder and fixed to turn with the power shaft, means adjustably carried by the cable lever to have a cable held therearound, a trip pawl carried by the trip cylinder to engage with the teeth of the ratchet hub to lock the trip cylinder to be turned with the shaft, means to release the trip pawl, and means to adjust the pawl releasing means to vary the degree of turning movement given to the trip cylinder.

5. A well drilling trip including in combination with a power shaft, a trip cylinder from which connection is made to a drilling tool, said trip cylinder being loosely mounted on the shaft, a ratchet hub fixedly mounted on the power shaft and located within the trip cylinder, a trip lever swingingly mounted on said trip cylinder, a trip pawl carried by the trip lever and extending into the trip cylinder, means to move and normally hold the trip lever in a fixed position so that the trip pawl is engaged with the teeth of the ratchet hub to lock the trip cylinder to turn with the shaft, and means to swing the trip lever to have movement so that the trip pawl is disengaged from the holding position when the desired turning movement of the trip cylinder has been accomplished.

6. A well drilling trip including in combination with a revolvably mounted power shaft, a trip cylinder loosely mounted on the power shaft, a ratchet hub fixedly mounted on the shaft within the trip cylinder, a trip pawl extending through the cylinder, means to normally urge the trip pawl to engage with the teeth of the ratchet hub, means by which a cable carrying a

44-603,327

drilling tool is connected with the trip cylinder, and means to render the trip pawl inoperative.

7. A well drilling trip including in combination with a power shaft, a trip cylinder loosely mounted on the power shaft and having a cable lever extending therefrom, cable holding means adjustably mounted on said cable lever, a ratchet hub fixedly mounted on the power shaft within the trip cylinder, a trip lever swingingly mounted on said trip cylinder, a trip pawl carried by one end of said trip lever and extended into the trip cylinder to engage with the teeth of the ratchet hub, means to normally urge the trip lever to a position that the trip pawl is operative, an adjusting lever mounted adjacent the mounting of the power shaft and provided with means by which the same is locked in adjusted positions, and means connected between the free end of the trip lever and said adjusting lever.

8. A well drilling trip including in combination with a power shaft, a trip cylinder loosely mounted on the power shaft and

having a cable lever extending therefrom, cable holding means adjustably mounted on said cable lever, a ratchet hub fixedly mounted on the power shaft within the trip cylinder, a trip lever swingingly mounted on 30 said trip cylinder, a trip pawl carried by one end of said trip lever and extended into the trip cylinder to engage with the teeth of the ratchet hub, means to normally urge the trip lever to a position that the 35 trip pawl is operative, an adjusting lever mounted adjacent the mounting of the power shaft and provided with means by which the same is locked in adjusted positions, means connected between the free end of 40 the trip lever and said adjusting lever, and means to be shifted to a position to lock the trip lever in such a position that the trip pawl is rendered inoperative.

In testimony whereof I affix my signature 45 in presence of two witnesses.

CLEVELAND W. WOODLAND.
